Atty's.

UNITED STATES PATENT OFFICE.

WARREN TRAVELL, OF NEW YORK, N. Y.

CARGO-HANDLING APPARATUS.

Application filed October 25, 1919. Serial No. 333,359.

To all whom it may concern:

Be it known that I, WARREN TRAVELL, citizen of the United States, residing at New York, in the county of New York and 5 State of New York, have invented certain new and useful Improvements in Cargo-Handling Apparatus, of which the following is a specification.

This invention relates to improvements 10 in cargo handling apparatus. It has been customary in American practice that the building called a freight shed on a pier stands close to the edge and occupies practically the entire width of the pier. In 15 changing such a pier to adapt it to cargo handling machinery as at present known, it is necessary to tear down both the shed and the pier, and to rebuild, in order to accommodate and to support the larger loads 20 imposed by cargo cranes of the common type. Such cranes are commonly of electric locomotive crane type, with a swinging boom at the edge of the pier outside of the shed, resting in part on the edge of the 25 roof and covering the marginal space between shed and water, with the boom projecting over the ship and then swinging around in the arc of a circle to a position where they may deposit their loads on the 30 marginal strip of pier. Goods thus deposited alongside the shed then have to be conveyed by hand trucks or other means to whatever part of the shed they are to occupy. If any 35 goods from the ship are to be put directly into a barge or other transhipping bottom on the other side of the pier they have to be again lifted, by another crane, and swung out over the edge, except in cases where the barge can be moored on the stream side 40 of the ship. Pier sheds as commonly existing in this country are not sufficiently strong to support such cranes, nor is there room therefor, between the pier shed and pier edge, nor sufficient strength in the pier 45 outside of the pier shed. It is an object of the present invention to make a cargo handling apparatus which shall both provide an apparatus which is an improvement over that above described, and also be able to 50 utilize such existing structures. This is accomplished by providing a gantry or framework spanning the roof of the pier shed at a suitable height above it, carrying a track for a hoisting carriage across it from edge 55 to edge of the pier and provided with booms extensible over the water in the direc-

tion of the length of the track. This is supported on high legs, one of which reaches down from each end of the gantry to the pier level where it has wheels on a single 60 rail track supported vertically by the harbor bottom and horizontally braced by the existing pier. The only requisite change in the building is the cutting of hatches through substantially the whole of its roof. 65 By this arrangement, a ship alongside can be unloaded at any point by running the gantry boom out over her and then, by the hoist and transporting carriage and way, lifting goods therefrom and running them to any 70 desired position across the width of the pier shed for lowering through a hatch uncovered for the purpose, or running them across to and out upon the boom extended at the other side of the pier and thence into a barge 75 alongside the pier. If it be desired to carry the goods lengthwise of the pier, that can be done by moving the gantry structure while the load is suspended; or the load can be shifted at any place across the width 80 of the pier to an interior conveyance. The major part of the unloading can ordinarily be done by direct hoist, horizontal transport and deposit to final position, the hoist and carriage operating at high speed, as compared with the slow swinging of a boom to the margin of the pier shed as in the wharf 85 cranes now common. The full width of the shed is as available as is the nearer margin; and the wall of the shed can be close to the 90 edge of the pier. If it be preferred, the framework or gantry can be otherwise mounted, or may extend only part way across, as for example, to the center, provided its inboard end is suitably supported; 95 and the invention may be applied in various other ways. It is intended that the patent shall cover, by suitable expression in the appended claim, whatever features of patentable novelty exist in the invention disclosed. 100

In the accompanying drawing; the figure is an end elevation in section through a pier embodying the invention.

Referring to the drawings, 10 indicates 105 the floor or level of a pier supported on piles 11 and having a pier house or shed 12 with a roof 13. This represents an existing pier to which the invention is to be applied, by considering that the piling structure 11 extends only as indicated by the dimension line *a* in the drawing. This 110

would be in accordance with common practice, there being but a narrow margin outside of the walls of the pier house, and the piling being adequate only for that with its 5 load. The piles *b* at each edge of the structure illustrated are added for the purposes of the invention, to carry the extra stresses resulting from the single rail of track carrying the overhead transverse way and boom. 10 However, they are not enough to carry that track alone. They are set rather close together and are at the top tied together with the existing closely set marginal piles and with the other piles across the full width of 15 the pier; and by this co-operation a relatively minor addition to the width of the pier is sufficient to form room and a firm marginal support for a single line of rails 14, one at each edge of the pier, on which 20 run wheels 15 supporting a gantry or framework having a trussed leg structure 16 rising to above the level of the roof, and there supporting the trussed bridge or framework 17 which carries the way on 25 which the carriage 19 runs transversely of the pier to any distance across it, or out on a boom on the other side. This is illustrated in position over a barge 20 on the side of the pier opposite the ship 21 which is being 30 loaded or unloaded. The carriage 19 is illustrated as being supported by a boom 22 which is extensible in the direction of its own length. Such a boom and carriage may be constructed and operated as described in my U. S. Letters Patent No. 35 1,305,631, entitled, Boom, dated June 3, 1919, the carriage running either on the boom or on a stationary way carried on the trussed

bridge, "stationary," that is, when the gantry is stationary, but carried by it whenever it moves; or it may be constructed and operated in any other suitable way. 40

In the drawings, sundry details of counterweight, reeving of ropes, etc., are omitted, as any suitable arrangements of these details may be used, either as shown in my said Letters Patent, or otherwise. The drawing shows a carriage 19 for each boom; each of which can run from its extreme outward position, as illustrated at the right in 45 the figure, inward over the boom and upon the permanent way as far as the rope which holds it runs, which may be either to a sheave at some point on the permanent way, or to a sheave at the outward extremity of the other boom, as can be understood from my 50 said patent; so that both carriages 19 can operate from the end of one boom to the other in case that is desirable; or can operate separately on their respective booms. 55

I claim as my invention:

The combination, with a complete, operative pier comprising a piling structure with floor and house in and over water, said house being close to the water edge of the 60 pier, of additional narrow piling structures extending along said house on both water margins of the first mentioned piling structure, tied thereto and supported thereby; and a gantry crane supported by said 65 marginal piling structures, bridging over the said house and co-operating therewith through openings in its roof.

Signed at New York, N. Y., this 22nd day of October, 1919.

WARREN TRAVELL.
